UNITED STATES PATENT OFFICE.

LEWIS E. FAGAN, OF MINNEAPOLIS, MINNESOTA.

DRY-PIPE VALVE.

No. 882,669.

Specification of Letters Patent. Patented March 24, 1908.

Application filed April 29, 1907. Serial No. 370,806.

To all whom it may concern:

Be it known that I, LEWIS E. FAGAN, a citizen of the United States, residing at Minneapolis, in the county of Hennepin and State of Minnesota, have invented certain new and useful Improvements in Dry-Pipe Valves, of which the following is a specification.

My invention relates to automatic fire-extinguisher systems, and particularly to the mechanisms employed therein known as dry-pipe valves. The purpose of such valve mechanisms is to prevent the admission of water into the distributing system by maintaining therein sufficient air pressure to hold the valves on their seats until a sprinkler head is opened and allows the air to escape, thereby reducing the air pressure and permitting the water pressure to unseat the valve and the water to flow into the distributing system.

The objects sought by this invention are to accelerate the entrance of the water into the distributing-system by providing a valve mechanism that will operate with a low air pressure to keep the system closed, regardless of the pressure of the water maintained in the supply system; and to insure the valve against being tripped by excessive water pressure caused by water-hammer, without carrying such high air pressure as would retard the action of the valve and delay the entry of the water into the distributing-system.

My improvements are illustrated in the accompanying drawings, in which—

Figure 1 is a longitudinal section of the valve with the front casing cut away, showing the valve in its closed position; Fig. 2 is also a longitudinal section of the valve, on the line A—A of Fig. 1; Fig. 3 is a section of the valve, similar to Fig. 1, showing the valve in the opened position; Fig. 4 is a horizontal section of the valve on the line B—B of Fig. 1; and Fig. 5 is a horizontal section on the line C—C of Fig. 1, with the cover plates 5 and 6 removed.

In the drawings 1 designates the valve case; 2, the wall separating the tumbler chamber 10 from the air-valve chamber 11; 3, the wall separating the air-valve chamber 11 from the water-valve chamber 12; 4, the water-valve chamber cover; 5, the air-valve

chamber cover; 6, the tumbler-chamber cover; 7, the auxiliary-air valve body, secured to the valve body 1 as shown in the drawings; 8, the auxiliary-air valve cover; and 9, the auxiliary-air valve chamber.

The water entrance to the casing is through the port 13, and the exit to the distributing system is through the port 14. The water-valve is arranged on the port 13 and the air-valve on an opening in the partition 3. A second opening 15 in the partition is provided for the movement of the strut 29 hereafter referred to.

The air-valve 19 rests on a seat 20 to close the part 21; and it is pivotally connected by a pin 18 to a yoke 17 which in turn is hinged to the casing by a pintle 16. By this arrangement the valve is adapted to swing by the water pressure from the position shown in Figs. 1 and 2 to that shown in Fig. 3.

A valve-seat 22 is provided for the port 13, on which rests the valve 23. A screw-cap 24 on the valve secures an adjusting screw 25 which engages a compression lever 26, and the latter has trunnions by means of which it is hinged to standards 27 that are secured to the bottom of the casing 1. This construction permits the valve and its connections to swing from the position shown in Figs. 1 and 2 to that shown in Fig. 3.

The valve 23 is held to its seat by means of the strut 29, the lower end of which bears on the lever 26 and the upper end of which is engaged by a lever 31 in the chamber 10. The strut is guided in its movements and prevented from being thrown out of position by guides 28 and by the walls of the opening 15.

The lever 31 is fulcrumed to brackets 30 on the inner wall of the chamber 10. A weight 32 is provided with a lower lateral arm 33, which the upturned narrow end of the lever 31 engages, and an upper lateral arm 34 having a transverse hole near its end. A pair of hangers 35 is secured to the top of the casing, and from them is suspended a bifurcated strut 36, the lower edge of which seats on the weight arm 33. The upper weight arm 34 extends through the space between the arms of the strut 36 and is connected to a strut 38 by a knife-edged horizontal pin 37. The upper end of the strut has a conical point that engages in a corresponding socket in the lower end of a pin

39 that extends downwardly from the auxiliary air-valve 40. This valve also has a pin 41 that projects upward into a guide-socket 42 formed in the cover 8 of the auxiliary air-valve casing. In the latter casing is an opening 43 for connection with the air system, or distributing system; in the wall of the chamber 11 is the draw-off opening 44; and in the wall of the chamber 12 is the opening 45 for connection with an alarm system.

In practice, the caps 4 and 6 are removed, the air-valve, auxiliary-valve, and water-valve are seated on their respective seats; 15 and air pressure is then put on the distributing-system and maintained to counterbalance the pressure exerted on the under side of the auxiliary-air valve 40 by the weight 32. The trigger-mechanism is then interposed between the auxiliary-air valve 40 and the compression-lever 26, as shown in Fig. 1, and the caps 4 and 6 are then replaced. As soon as the sprinkler-head is opened the air in the distributing-system escapes and the 25 pressure on the auxiliary-air valve is released. Upon such release of pressure, there no longer being pressure on the weight-arm 34, the weight descends, rocking on the contact points of the lever 31 and strut 36, and thereby 30 by swinging the arm 34 and the strut 38 upward and thus lifting the valve 40 off its seat. The downward movement of the weight will serve, as is obvious, to move the strut 36 out of vertical alinement with the 35 tip of the lever 31, and thereby free the latter. The lever 31 being free the upward pressure of the water upon the strut 29 will lift it, together with the lever 31, and in doing so will lift the valve 23 and swing it and the 40 compression lever 26 to one side. The water rushing in will cause the swinging air-valve 19 to swing to one side, thus leaving a clear and unobstructed passage for the water into the distributing-system through the exit 14. 45 The water entering the water-valve chamber 12 will be transmitted to the alarm-system, through the port 45, to operate the alarm the moment the valve is opened.

Having described my invention, what I 50 claim and desire to secure by Letters Patent is—

1. In a dry-pipe valve, a casing providing main chambers, a supplemental chamber and an auxiliary air-chamber, air and water valves in the main chambers, a valve in the auxiliary chamber having a stem extending into the supplemental chamber, a strut extending from the water-valve into the latter chamber, and a trigger mechanism 55 connecting said stem and strut and comprising a lever, a pivoted strut, and a weight provided with a pair of arms and a strut, substantially as set forth.

2. In a dry-pipe valve, a trigger mechanism comprising a lever, a pivoted strut, a depending swinging strut, and a weight provided with a pair of arms and a strut, substantially as set forth. 65

3. In a dry-pipe valve, a trigger mechanism, comprising a lever fulcrumed to the 70 casing, a swinging strut depending from the casing, a free weight provided with a pair of arms and a strut, substantially as set forth.

4. In a dry-pipe valve, a trigger mechanism, comprising a lever fulcrumed to the 75 casing, a swinging strut depending from the casing, a free weight having an arm for engaging said strut and lever and another arm provided with a pivoted strut, substantially as set forth. 80

5. In a dry-pipe valve, the combination with a strut for the water-valve and the stem of an auxiliary air-valve, of a trigger mechanism comprising a lever fulcrumed to the 85 casing, a swinging strut depending from the casing, a free weight provided with a pair of arms and a strut, substantially as set forth.

6. In a dry-pipe valve, the combination with a strut for the water-valve and the stem of an auxiliary air-valve, of a trigger mechanism comprising a lever fulcrumed to the 90 casing, a swinging strut depending from the casing, a free weight having a lower arm for engaging the lever strut and said lever, and an upper arm provided with a pivoted strut 95 for engaging said valve stem, substantially as set forth.

7. In a dry-pipe valve, a casing providing main chambers, a supplemental chamber and an auxiliary air-chamber, air and water 100 valves in the main chambers, a strut for holding the water-valve to its seat, a lever in the supplemental chamber for holding the strut in place, a valve for the auxiliary chamber, a stem therefor, a pivoted strut in 105 the supplemental chamber, and a weight provided with arms and a strut, substantially as set forth.

8. In a dry-pipe valve, a casing providing main chambers, a supplemental chamber 110 and an auxiliary air-chamber, air and water valves in the main chambers, a strut for holding the water valve to its seat, a lever in the supplemental chamber for holding the strut in place, a valve for the auxiliary chamber, a stem therefor, and tripping devices operatively connecting said stem with said lever, and comprising a swinging strut depending from the casing, a free weight provided with a pair of arms and a strut, 115 substantially as set forth. 120

9. In a dry-pipe valve, a casing providing main chambers and a supplemental chamber, an air-valve and a water-valve in the former and a tripping mechanism in the 125 latter chamber, comprising a lever, a pivoted

strut, and a weight provided with a pair of arms and a strut, a strut for connecting the water-valve with the tripping mechanism, and an auxiliary air-valve connected with the trigger mechanism for controlling its operation, substantially as set forth.

In testimony whereof I have signed my

name to this specification in the presence of two subscribing witnesses this 25th day of April, 1907.

LEWIS E. FAGAN.
